LATCH FOR AUTOMOBILE FENDER
SHROUDSArthur Claud-Mantle, Trumbull, Conn., assignor
to The Bassick Company, Bridgeport, Conn., a
corporation of Connecticut

Application October 1, 1934, Serial No. 746,286

9 Claims. (Cl. 70—14)

The present invention relates to an improved latch for an automobile fender shroud, and has for an object to provide a latch which will securely hold the shroud against vibration and looseness, and which may be actuated with facility to both secure and release the shroud. It is particularly proposed to provide a latch in which the latching bolt has both rectilinear and swinging movement, to the end that the latch will engage the shroud to exert both lifting pressure to hold the shroud up against the fender and lateral drawing pressure to pull the fender toward the shroud, thus not only tightly holding the shroud in place, but providing a substantial reinforcing structure for the fender. Another object is to provide a latch in which the usual spring means employed in latches is dispensed with, the tension for holding the latch in operative position being supplied by pressure exerted by the drawing together of the edges of the shroud and fender. A further object is to provide, in one embodiment of the invention, remote control actuating means for the latch which may be disposed at any desired point on the shroud.

With the above and other objects in view, embodiments of the invention are shown in the accompanying drawings, and these embodiments will be hereinafter more fully described with reference thereto and the invention will be finally pointed out in the claims.

In the drawings:

Fig. 1 is an outside elevation of the contiguous portions of the fender and shroud provided with the latch, according to an exemplary embodiment of my invention, and in which the actuating means is at a remote point from the casing.

Fig. 2 is a side elevation, reduced, showing the entire fender and shroud.

Fig. 3 is a horizontal sectional view, taken along the line 3—3 of Fig. 1.

Fig. 4 is an inner side elevation, with a portion of the cover plate broken away, the full lines showing the latching or projected position, and the dot-and-dash lines showing the released positions.

Fig. 5 is a forward edge view of the latch, a portion of the edge flange of the shroud being broken away.

Fig. 6 is an inner side elevation of a modified form of latch, according to my invention, and in which the actuating means is mounted in the latch casing.

Fig. 7 is a horizontal sectional view, taken along the line 7—7 of Fig. 6.

Fig. 8 is a forward edge view of the latch, a

portion of the edge flange of the shroud being broken away.

Fig. 9 is a vertical sectional view, taken along the line 9—9 of Fig. 6.

Fig. 10 is an inner side elevation of the latch, separated from the shroud and with the cover plate being removed, the full lines showing the latching or projected position, and the dot-and-dash lines showing the released or retracted position.

Similar reference characters indicate corresponding parts throughout the several figures of the drawings.

Referring to the drawings, the latch, according to the exemplary illustrated embodiment of the invention, shown in Figs. 1 to 5, comprises a casing consisting of a mounting plate 10, having a right angularly bent forward wall flange 11 and a right angularly bent rear wall flange 12, the upper edge of the mounting plate being inclined upwardly from the front to the rear. The mounting plate is secured to the edge flange 13 of the shroud 14 by means of screws 15—15 engaged through inwardly flanged holes 16—16 in the shroud flange 13 and screwed into nuts 17—17 secured in holes 18—18 in the forward wall flange 11, these nuts being secured by swedging, as at 19—19, and being flattened at opposed sides to engage the inner surfaces of the casing to prevent turning. At the lower edge of the plate 10 there is provided a downwardly extending portion 20 having a right angular flange 21 at its lower end which is secured to the shroud flange 11 by a bolt 22 engaging a nut 23 secured to the flange 22 by swedging. The rear wall flange 12 extends to the base of the portion 20 to reinforce it. The casing is completed by means of a cover plate 24 having right angularly bent flanges 25 and 26 at its respective upper and lower edges, and which are secured to the plate 10 by means of bent over lugs 27 engaged through slots 28 in the plate 10. The flange 12 of the plate 10 is secured to the lower plate by means of bent over lugs 29 provided thereon and engaged through slots 30 in the cover plate.

An elongated bolt slot 31 is provided in the forward wall flange 11, and a lip 32 provided in the cover plate is engaged therein against one edge, this lip being inwardly offset from the cover plate by inwardly embossing the latter, as at 33. The cover plate is outwardly embossed as at 34—34, above and below the inwardly embossed portion 33, to provide pockets for the nuts 17—17. In the rear wall there is provided a slot 35 for the actuating bar, hereinafter more fully referred to,

the upper and lower ends of this slot having inwardly bent bearing flanges 36—36 for engaging the upper and lower edges of said bar.

The latch bolt 37 has its forward end engaged in the slot 31, and in which it is adapted to have rectilinear and swinging movement, as will hereinafter more fully appear. The bolt is provided at its intermediate portion with a slot 38 engaged by a roller 39 mounted upon a stud 40 secured between the mounting plate 10 and cover plate 24 of the casing, the stud being shouldered at its ends and engaged in holes 41 and 42 respectively provided in the plates 10 and 24. The lower edge of the bolt is provided with a straight edge portion 43, parallel to the rectilinear movement of the bolt, and engaged by a guide roller 44 mounted on a stud 45 secured between the plates 10 and 24 in a similar manner to the stud 40. In the retracted operative position of the bolt the roller 39 is at the forward end of the slot 38 and the rearward edge of the bolt is rearwardly spaced from the roller 44. In the rectilinearly projected and inwardly swung positions the roller 39 is at the rearward end of the slot 38, and the rearward edge of the bolt, which is arcuately shaped in concentric relation to the rearward end of the slot 38, as at 46, rolls upon the roller 44 as the bolt is swung.

The actuating bar 47 extending through the slot 35 is connected to the bolt by means of a pair of link members 48—48, these link members being connected to the bar by a pivot stud 49 and to the bolt by a pivot stud 50, the ends of these studs projecting beyond the outer surfaces of the link members and being guided in grooves 51 and 52, respectively provided in the plates 10 and 24 and suitably shaped to guide the movements of the studs as the bolt is operated. The stud 50 is connected to the bolt at a point rearwardly of and below the slot 38. A hook portion 53 is provided at the fender engaging end of the bolt.

The manually operable actuating means for operating the latch is located at a remote point therefrom, being shown as at the center of the shroud near its lower edge. At this central portion the shroud is provided with an ornamental member 54 having a hole 55 therein in which a cup 56 is set, the shroud being apertured at 57 in register with an aperture 58 in the cup. A stud 59 having a hexagonal head 60 is engaged in the apertures 57 and 58, and is secured to a crank lever 61, the stud being screw-threaded at its inner end and provided with opposed flats 62—62 and being engaged in a correspondingly shaped hole 63 in the crank lever, to which it is fixedly secured by a nut 64 screwed upon the stud. A washer 65 is interposed between the crank lever and the inner surface of the shroud.

The bar 47 is pivotally connected at 66 to the crank lever at a point rearwardly of the axis of the stud 59, and at a point forwardly of said axis the lever is provided with a right angularly bent flange 67 which abuts the lower edge of the bar 47 in the operative position, the pivotal connection 66 in this operative position being below a line intersecting the axes of the stud 49 and the axis of the stud 59, so that forward pull on the bar exerts a pull on the crank lever below its dead center and thereby locks it in place. The bar 47 is arched as at 68, to clear the nut 64.

The shroud 14 is provided at its flanged edge 13 with a facing 69 of rubber secured thereto, and is adapted to engage the inwardly curled edge flange 70 of the fender 71. Slots 72 and 73 are respectively provided in the shroud flange 13 and

in the rubber facing 69 through which the bolt moves, and a slot 74 is provided in the flange 70 of the fender, the fender flange being preferably reinforced at its inner side by a slotted metal plate 75.

As shown in Fig. 2 the shroud is provided at the opposite side from the latch with a fixed hook 76, which in mounting the shroud is first engaged in a slot 77 in the edge of the fender whereupon the other end of the shroud is lifted up about the hook 76 as a fulcrum to bring the latch into relation with the fender slot 74.

The dot-and-dash lines A, Fig. 4, indicate the inoperative or retracted position of the latch bolt, the arcuate edge portion 46 of the bolt engaging the roller 44 and holding the bolt with the roller 39 engaged at the rearward end of the slot 38, the end of the bolt being swung upwardly in the slot 31. In order to bring the latch to operative position the stud 59 and crank lever 68 are turned by engaging a suitable wrench or tool with the hexagonal head 60 causing the bar 47 to be retracted and through the link connections 48—48 swinging the bolt downwardly to the horizontal position indicated by the dot-and-dash lines B. As long as the arcuate portion 46 remains in contact with the roller 44 the bolt swings about the axis of the roller 39 without any rectilinear movement relatively thereto. During this movement the bolt hook 53 enters the fender slot 74 and presses the shroud upwardly as the bolt engages the lower end of the slot and continues its swinging movement. As the bolt assumes a horizontal position, and the lower edge surface 43 comes into contact with the roller 42, the bolt is drawn inwardly to the full line position, the hooked end 53 tightly drawing the fender toward the shroud and compressing the rubber facing 69. During this movement the pivot 66 passes over the dead center along the line intersecting the axis of the stud 49 and 59, the pull exerted on the bar 47 by the pressure of the compressed rubber facing 69 causing the crank lever to snap into its operative position with the flange 67 abutting the lower edge of the bar, and in which position the parts are locked. To disengage the catch the stud 59 and crank lever 61 are turned in the opposite direction, the pressure being released as the pivot 66 passes over the dead center. The bolt first moves outwardly to the position indicated by the dot-and-dash lines B, and then swings upwardly to the position indicated by the dot-and-dash lines A to clear the fender slot.

In Figs. 6 to 10 I have shown a modified form of the invention in which the actuating means is mounted in the latch casing. The casing is substantially similar in construction and mounting to that of the first embodiment, its proportions being somewhat different, however, to accommodate the actuating means. The bolt is also similar and is mounted in relation to the rollers 39 and 44 in the same manner. These parts are therefore given the same reference characters as the first embodiment.

The actuating means consists of a hub member 75 having a square or other suitable non-circular passage 77 therethrough, and upon which there is secured a crank plate 78, the hub being provided for this purpose with milled slots 79 in its periphery in which lugs 80 on the plate engage. The ends of the hub are shouldered and are rotatably engaged in opposed bearing apertures 81 and 82 in the mounting plate 10 and cover plate 24 of the casing. A hole 83 is provided in the shroud in line with the passage 77 and the latter is pref-

erably beveled at its end, as at 84 to facilitate the engagement of a suitable operating tool therein. The inner end of the bolt 37 is connected to the crank plate by means of links 85-85 pivotally connected to the bolt by a stud 86 and pivotally connected to the crank plate by a stud 87, the ends of these studs projecting beyond the links and being engaged in guide grooves 88 and 89 respectively provided in the casing plates 10 and 10 24, and which are shaped to guide their movements as the latch is actuated.

A cross-pin 90 is secured between the cross-plates 10 and 24 above the bolt to prevent it from being forced upwardly during its rectilinear movements, and a similar cross-pin 91 is provided in relation to the crank plate 78 and against which it abuts in its operative position, as indicated in full lines in Fig. 10.

The pivot 87, it will be noted, is beyond the dead center of the line intersecting the pivot 86 and the axis of the hub 76, so that the forward pressure exerted on the bolt by compression of the rubber facing exerts pressure beyond dead center to lock the parts in position. To disengage the catch the crank plate is turned in clock-wise direction from the full line position shown in Fig. 10 the pressure being released as the pivot 87 passes over the dead center, the bolt moving first rectilinearly to the position indicated by the dot-and-dash lines B, and then being swung to the retracted position indicated by the dot-and-dash lines A. To engage the catch the crank plate is turned in counter-clockwise direction, as will be obvious.

I have illustrated and described preferred and satisfactory embodiments of my invention but it will be obvious that changes may be made therein, within the spirit and scope thereof, as defined in the appended claims.

Having thus described my invention what I claim and desire to secure by Letters Patent is:—

1. In a latch of the character described, a casing, a latch bolt in said casing, a pivotal mounting for said bolt with respect to which it is adapted to have rectilinear movement and swinging movement at one end of said rectilinear movement, a cam surface on said bolt including a portion parallel to said rectilinear movement and a portion which at said one end of rectilinear movement is concentric to the axis of said swinging movement, guide means carried by said casing and adapted to successively engage said parallel and concentric portions of said cam surface during said rectilinear and swinging movements, a rotatable actuating member, and means connected between said actuating member and said bolt adapted to impart sliding and swinging movement to said bolt upon actuation of said actuating member.

2. In a latch of the character described, a casing, a latch bolt, a pivotal mounting for said bolt with respect to which it is adapted to have rectilinear and swinging movement, a rotatable actuating member remote from said casing, a connecting member between said actuating member and said bolt adapted to impart sliding and swinging movement to said bolt upon actuation of said actuating member.

3. In a latch of the character described, a casing, a latch bolt, a pivotal mounting for said bolt with respect to which it is adapted to have rectilinear and swinging movement, a rotatable actuating member remote from said casing, a connecting bar pivotally connected at one end to said actuating member and slidably engaged at its

other end with said casing, and link means pivotally connected between said bar and said bolt, said bar and link means adapted to impart sliding and swinging movement to said bolt upon actuation of said actuating member.

4. In a latch of the character described, a casing, a latch bolt in said casing, a pivotal mounting for said bolt with respect to which it is adapted to have rectilinear and swinging movement, a cam surface on said bolt including a portion parallel to said rectilinear movement and a portion concentric to the axis of said swinging movement, guide means carried by said casing and engaging said cam surface, a rotatable actuating member, and means connected between said actuating member and said bolt adapted to impart sliding and swinging movement to said bolt upon actuation of said actuating member, outward pull on said bolt adapted to exert pull on said actuating means at a point in its bolt actuating movement past the dead center of the actuating means to retain it against reverse movement.

5. In a latch of the character described, a casing, a latch bolt in said casing, a pivotal mounting for said bolt with respect to which it is adapted to have rectilinear and swinging movement, a cam surface on said bolt including a portion parallel to said rectilinear movement and a portion concentric to the axis of said swinging movement, guide means carried by said casing and engaging said cam surface, a rotatable actuating member, and means connected between said actuating member and said bolt adapted to impart sliding and swinging movement to said bolt upon actuation of said actuating member, outward pull on said bolt adapted to exert pull on said actuating means at a point in its bolt actuating movement past the dead center of the actuating means to retain it against reverse movement, and stop means for limiting the movement of said actuating member through said pull exerted thereon.

6. In a latch of the character described, a casing, a latch bolt in said casing, a pivotal mounting for said bolt with respect to which it is adapted to have rectilinear and swinging movement, a cam surface on said bolt including a portion parallel to said rectilinear movement and a portion concentric to the axis of said swinging movement, guide means carried by said casing and engaging said cam surface, a rotatable actuating member remote from said casing, a connecting member between said actuating member and said bolt adapted to impart sliding and swinging movement to said bolt upon actuation of said actuating member.

7. In a latch of the character described, a casing, a latch bolt in said casing, a pivotal mounting for said bolt with respect to which it is adapted to have rectilinear and swinging movement, a cam surface on said bolt including a portion parallel to said rectilinear movement and a portion concentric to the axis of said swinging movement, guide means carried by said casing and engaging said cam surface, a rotatable actuating member remote from said casing, and a connecting bar pivotally connected at one end to said actuating member and slidably engaged at its other end with said casing, and link means pivotally connected between said bar and said bolt, said bar and link means adapted to impart sliding and swinging movement to said bolt upon actuation of said actuating member.

8. In a latch of the character described, a casing, a latch bolt in said casing, a pivotal mounting for said bolt with respect to which it is adapted to

have rectilinear and swinging movement, a cam surface on said bolt including a portion parallel to said rectilinear movement and a portion concentric to the axis of said swinging movement,
5 guide means carried by said casing and engaging said cam surface, a rotatable actuating member remote from said casing, and a connecting bar pivotally connected at one end to said actuating member and slidably engaged at its other end
10 with said casing, and link means pivotally connected between said bar and said bolt, said bar and link means adapted to impart sliding and swinging movement to said bolt upon actuation of said actuating member, outward pull on said bolt adapted to exert pull on said actuating means at
15 a point in its bolt actuating movement past the dead center of the actuating means to retain it against reverse movement.

9. In a latch of the character described, a cas-

ing, a latch bolt in said casing, a pivotal mounting for said bolt with respect to which it is adapted to have rectilinear and swinging movement, a cam surface on said bolt including a portion parallel to said rectilinear movement and a portion concentric to the axis of said swinging movement, guide means carried by said casing, and engaging said cam surface, a rotatable actuating member carried by said casing, and means connected between said actuating member and
10 said bolt adapted to impart sliding and swinging movement to said bolt upon actuation of said actuating member, outward pull on said bolt adapted to exert pull on said actuating means at a point in its bolt actuating movement past the
15 dead center of the actuating means to retain it against reverse movement.

ARTHUR CLAUD-MANTLE
